INVENTOR

Burt F. Upham

By Charles G. Cope
Atty.

UNITED STATES PATENT OFFICE.

BURT F. UPHAM, OF BROOKLINE, MASSACHUSETTS, ASSIGNOR TO MILLER SAW-TRIMMER COMPANY, OF PITTSBURGH, PENNSYLVANIA, A CORPORATION OF PENNSYLVANIA.

MECHANICAL MOVEMENT.

Application filed December 14, 1925, Serial No. 75,160. Renewed June 9, 1928.

My invention pertains to mechanical movements, and relates especially to mechanism for imparting a reciprocating motion to a relatively heavy body, such as the bed of a printing press, in such manner as to provide an easy slowing down, stopping and starting in a reverse direction.

The mechanical movement according to my present invention is of the same broad type as those described in Patent No. 1,094,405 granted to me April 21, 1914, and Patent No. 1,398,817 granted November 29, 1921, to Frank R. Belluiche and myself. It is an object of my invention to improve upon the movements disclosed by the said prior patents, and particularly upon the movement disclosed by the said Patent No. 1,398,817, in such manner as to enable a more compact machine to be obtained by reducing the proportionate size of the reciprocating body, to facilitate and cheapen manufacture and minimize upkeep, and to increase the possibility of speed by reducing the proportionate weight of the reciprocating body. Other objects of my invention will appear from the following specification taken in connection with the claims annexed thereto.

I have described, by way of example, in the following specification, and shown in the accompanying drawings, one form of mechanical movement in which my invention may be embodied, the same being applied to a printing press as a means for reciprocating the bed of the latter. It is to be understood, however, that my invention may be embodied in other forms, and that changes may be made in the form described and shown, without exceeding the scope thereof, as defined in the appended claims.

In the drawings:

Fig. 1 is a partial side elevation of a bed and cylinder printing press embodying my present invention as a means for effecting the reciprocation of the type-bed, the latter being shown in one of its extreme end positions;

Fig. 2 is a sectional end view, the section being taken on the line 2—2 of Fig. 1;

Fig. 3 is a sectional elevation, taken on the line 3—3 of Fig. 2, looking in the direction of the arrows, the parts, however, being shown in the position in which the type-bed

has just concluded its uniform movement towards the right and is just about to be slowed down prior to reversal;

Fig. 4 is a section on the line 4—4 of Fig. 3, looking in the direction of the arrows;

Fig. 5 is a perspective view of one of the wrist pins;

Fig. 6 is a detail section taken on the line 60 5—5 of Fig. 3;

Fig. 7 is a section on the line 7—7 of Fig. 6, looking towards the right;

Fig. 8 is a similar section but looking towards the left;

Figs. 9 and 10 are diagrams illustrating the principle of operation of the movement in effecting stoppage, reverse and restarting, and

Fig. 11 is a diagram illustrating the manner of operation of the guard heads with which the wrist pins are provided.

The press comprises a pair of main side frames 10 and 11 carrying between them sub-frames 12 and 13. At the upper edges 75 of the latter are formed tracks for the reception of rolls 14, and upon these latter the bed 15 runs in the well known manner. To the underside of the bed are secured a pair of racks 16 and 17, one on each side of the longitudinal center line of the bed. One of these racks is utilized in effecting the uniform movement of the bed in one direction, the other being utilized for effecting such uniform movement in the opposite direction. 80 The non-uniform movements of the bed, in stopping, reversing and starting in the opposite direction, are effected by reversing rolls mounted on wrist pins carried by reversing wheels, such wrist pins engaging reversing shoes formed upon a hanger 18 centrally disposed with respect to the bed and extending downwardly from the latter.

A main drive shaft 19 (Figs. 1 and 2) is mounted in suitable bearings carried by the 95 sub-frames 12 and 13 and has secured thereto a pinion 20 which meshes with a gear 21 secured to a shaft 22. The latter is mounted in a large bearing 23 carried by the sub-frame 12 and extends outward through the 100 side frame 10, having secured thereto, at its outer end, a large gear 24. The latter meshes with the gear 25 of the impression cylinder 26. The gears 24 and 25 are of the

same diameter, so that the cylinder rotates uniformly with the gear 21.

A stub shaft 27 (Figs. 1 to 4) is mounted in a bearing of the sub-frame 12 and carries the right-hand reversing wheel 28, which is a gear wheel of the same diameter as, and meshing with, the gear 21. The wheel 28 is termed the right-hand reversing wheel because it carries a wrist pin and reversing roll, and effects the slowing down, reversing and restarting of the bed at the right-hand end of the travel of the latter.

Mounted on a stub shaft 29 carried by a bearing of the sub-frame 12, and longitudinally movable on such shaft, is the left-hand bed-driving pinion 30, so called because it effects the uniform movement of the type bed in the left-hand direction. This pinion 30 meshes continuously with the teeth of the reversing wheel 28, but, by longitudinal movement on its shaft 29, it can be moved into and out of operative relation with the bed rack 16.

The left-hand reversing wheel 31 is carried by a stub shaft 32 of the sub-frame 13 and is a gear wheel of the same diameter as the right hand reversing wheel 28 and gear 21. It is driven by a pinion 33 on the main drive shaft 19, this pinion being of the same diameter as the pinion 20 which drives the gear 21. With the teeth of the wheel 31 meshes the right-hand bed-driving pinion 34, which is mounted on a stub shaft 35 carried by a bearing of the sub-frame 13. This pinion is longitudinally movable upon a shaft, into and out of operative relation with the bed rack 17.

The bed racks 16 and 17 are of a length equal to one-half the pitch circumferences of the reversing wheels 28, 31; and, from this and the preceding description of the gearing, it will be understood that the press now being described is of the two revolution type, having what is known as the two to one bed motion.

Secured to the shaft 22, on the outside of the frame 10, is a pinion 36 which engages with a gear 37 carried by the cam shaft 38. The gear 37 is twice the diameter of the pinion 36; so that the cam shaft makes one revolution for each cycle of the press. Upon the shaft 38 is secured a cam 39 having a groove 40 in which engages a roller carried by the lower end of a cam lever 41. The cam lever 41 is pivoted to the sub-frame 13 (Figs 3 and 4) and has pivoted thereto, at its upper end, a block which engages in a channel 42 formed in the hub of the right-hand bed-driving pinion 34. Pivoted to the sub-frame 12, and connected to the lower end of the cam lever 41 by a link 43, is a second cam lever 44 having pivoted to its upper end a block which engages a channel 45 of the left-hand bed-driving pinion 30. The groove 40 of the cam 39 is such that the cam

levers 41, 44, will be moved transversely to the right (Fig. 4) during one quarter, held stationary during the next quarter, moved to the left during the next quarter, and held stationary during the last quarter, of the 70 cycle.

In the position of the parts shown in Figs. 3 and 4, the cam 39 has held the right-hand bed-driving pinion 34 in engagement with the bed rack 17 for a quarter cycle of the 75 press, which is one half revolution of the left-hand reversing wheel 31, and has held the left-hand bed-driving pinion 30 out of engagement with the bed rack 16 during this period. Thus the bed has just been given 80 a uniform movement equal to one half the pitch circumference of the reversing wheel. At this point the rack 17 leaves the pinion 34 lengthwise. During the next quarter cycle, during which the racks 16 and 17 are 85 out of engagement with the pinions 30 and 34 and the reversing operation is taking place, the cam 39 will shift the pinions 30 and 34 to the left, thus moving the pinion 34 90 out of the path of the rack 17, and bringing the pinion 30 into the path of the rack 16 so as to be ready to impart the uniform movement to the bed after the reverse has been completed.

Each of the reversing wheels carries a 95 wrist pin on which is mounted a reversing roll for engaging the shoes carried by the hanger 18 of the bed. Taking the right-hand reversing wheel 28,—one of its spokes is enlarged so as to form a bearing 51 in 100 which is keyed the shank 46 of a wrist pin 47, the latter being held in place in the bearing by a nut 48 (Figs. 5 and 6). Upon the wrist pin is revolvably mounted a reversing roll 49, the latter being held in place by a 105 guard head 50 on the wrist pin, which head confines the roll between itself and the face of the bearing 51. The guard head 50 is of segment shape, having an arc-shaped face 58 and a flat face 59, the segment being less than one half of a circle which is of the same diameter as the roll 49. The left-hand reversing wheel is provided with a similarly arranged wrist pin having a similar segment shaped guard head 50^a and carrying 115 a reversing roll 49^a. The reversing rolls co-operate with reversing shoes which are set at an angle of 45° to the plane of movement of the bed; so that the wrist pins must be located within the pitch line of 120 the reversing wheels. The manner of determining the radial distance of the wrist pins from the axes of the reversing wheels is fully set forth in Patent No. 1,094,405, 125 above referred to.

The hanger 18 of the bed is formed, on its front face, and on the left hand side of its center, with a flange 52 disposed at an angle of 45° to the vertical. This flange 130 is of a depth somewhat greater than the

combined widths of the reversing roll 49 and guard head 50. Secured to the face of the flange 52 is an effective shoe 53 of a width only equal to that of the roll 49; so that the shoe will be engaged by the reversing roll 49, but will not be engaged by the guard head 50. The hanger 18 is also formed with a second flange 54 parallel with the flange 52, the said flange being of a depth equal to that of the flange 52 for a short distance at the top end, but being narrow for the remainder of its length. To the flange 54 is secured a guard shoe, at the top end of which is a portion 55 of a width equal to the combined widths of the reversing roll 49 and guard head 50, the remaining part 56 of the guard shoe being of a width only equal to that of the guard head 50. Thus the effective shoe 53 can never be engaged by the guard head 50, while the narrow lower part 56 of the guard shoe can never be engaged by the reversing roll 49. The effective shoe 53 and the guard shoe are spaced apart by a distance equal to the diameter of the reversing roll 49, and form between them what may be termed the right-hand reversing channel 57. At its right-hand end, and on its rear face, the hanger 18 is formed with flanges and provided with shoes similar to those above described, such shoes forming between them what may be termed the left-hand reversing channel 57^a.

Referring now to Fig. 3, this figure shows the parts just as the bed rack 17 is leaving the right-hand bed-driving pinion 34. At this time the effective shoe 53 will have arrived in contact with the reversing roll 49, which latter will be just entering upward between such shoe and the upper portion 55 of the guard shoe. Supposing the press to be operating at speed, the momentum of the bed, which has just finished its uniform movement towards the right, will crowd the effective shoe 53 against the reversing roll 49. As the reversing roll moves from the point *a* to the point *b* (Fig. 9), the bed will be gradually retarded by the reversing roll, and finally stopped when the point *b* is reached. During this time the reversing roll travels upward and then downward in the channel 57 between the effective shoe 53 and the upper portion 55 of the guard shoe. As the reversing roll passes from the point *b* to the point *c*, it will operate upon the effective shoe 53 to force the bed to the left, until, when the point *c* is reached, the correct face speed for the uniform movement of the bed will have been attained. At this point the left-hand bed-driving pinion 30 will be engaged by the bed rack 16 and will thereafter drive the bed.

When the press is being turned over slowly by hand, the bed will, of course, have no such momentum as would complete its

movement after the rack has left the bed-driving pinion. In that case, the reversing roll 49, by its engagement with the upper portion 55 of the guard shoe, effects the completion of the movement of the bed. 70

It will be noted that the construction of my present invention differs from the two to one bed motion of the said Upham and Belluche Patent No. 1,398,817, among other things, in that each reversing shoe is disposed on the side of the center of the bed opposite to that at which the reversing operation takes place; whereas, in the said Upham and Belluche patent, each reversing shoe is disposed on the same side of the center of the bed as that at which the reversing operation takes place. That is to say, in the present construction the effective shoe 53, which operates during the reverse at the right-hand end of the bed travel, is placed at the left-hand side of the center of the bed; whereas, in the construction of said Upham and Belluche patent the effective shoe 3^a, which operates during the reverse at the right-hand end of the bed travel, is placed at the right-hand side of the center of the bed. 75 80 85 90

The construction according to the present invention has several advantages, one of which is that, whilst a complete holding down action is retained, the length of the bed can be reduced to a minimum. In the construction shown, the length of the bed is but very slightly greater than the amount of the uniform bed travel. The reason for this will be apparent from the diagrams, Figs. 9 and 10. In Fig. 9 the parts are shown in full lines in the position they assume just as its bed rack leaves the right-hand bed-driving pinion, the effective shoe 53 having just arrived in contact with the reversing roll 49. The retarding effect of the reversing roll will react on the bed along a line *d* normal to the shoe 53. As will be seen, this line intersects the line of travel of the bed intermediate the ends of the bed. In dotted lines in the same figure the parts are shown in a position they assume just before the reverse takes place; and it will be seen that the line *e* of reaction of the retarding force, still intersects the line of the bed travel intermediate the ends of the bed. The parts are shown in full lines in Fig. 10 in the position they assume when the bed is being started again shortly after the reverse. The reversing roll 49, operating to start the bed, will exercise a force which will react on the bed along the line *f*, normal to the shoe 53. In dotted lines in the same figure, the parts are shown in the position they assume when the reverse has been completed and the left-hand bed-driving pinion is just engaging its bed rack, the driving force of the reversing roll reacting on the bed along the line *g*. It will be seen 100 105 110 115 120 125 130

that both the lines *f* and *g* intersect the line of travel of the bed intermediate the ends of the latter. Thus the forces effective both in retarding the bed and starting it again 5 in the opposite direction are applied in a very condensed space with respect to the line of travel of the bed, which enables a relatively short bed to be employed without the existence of any tendency of the retarding and starting forces to tilt the bed end- 10 wise. This tends towards lightness of the bed, and reduction of the floor area required by the press. I am enabled to obtain this advantage particularly in a two to one as 15 differentiated from a three to one bed motion, by the construction of gearing employed, and especially by the arrangement in which the reversing shoes open in opposite directions.

20 The guard heads 50 and 50^a of the wrist pins and the shoe construction to cooperate therewith, form the subject of the copending application of Frank R. Belluche filed of even date herewith entitled Mechanical 25 movements. It will be noted that these guard heads have no effect during the ordinary running of the bed at speed, since, under these conditions, the pressure is always between the effective shoes and the 30 reversing rolls, and these effective shoes are not wide enough to be contacted by the curved faces 58 of the guard heads. The prime purpose of these guard heads is to prevent accidental movement of the bed out of 35 its proper position with respect to the reversing rolls, to prevent over-running of the bed during starting, and to enable the press to be turned over in a reverse direction when desired. The manner in which the guard 40 heads operate will be understood from the diagram, Fig. 11. In the full-line position indicated at *h* in this diagram the reversing shoes, during the uniform movement of the bed towards the right, are approaching the 45 wrist pin 47, which is moving upward in its travel. It will be observed that if the lower part 56 of the guard shoe were of full height, it would collide with the reversing roll. However, this part of the guard shoe being 50 only of a height equal to the width of the guard head 50, the flat side 59 of the latter can enter beneath the end of the shoe. The position indicated by *i* shows how the flat side of the guard head thus enters beneath 55 the shoe 56. In the position indicated at *a*, the reversing roll has started to operate, but the curved edge 58 of the guard head is not operative because the effective shoe is not wide enough to be engaged by it. In the 60 position indicated at *b* the reversing roll is just leaving the space between the effective shoe and the wide part 55 of the guard shoe, and it will be seen that the curved face 58 of the guard head is in position to engage the 65 narrow part 56 of the guard shoe. In the

position indicated at *c*, which is the position at which the uniform movement of the bed starts, the curved face 58 of the guard head is still in position to be engaged by the narrow part 56 of the guard shoe, but is just 70 about to leave the same in a downward direction.

The only time when the bed would be otherwise out of control is during the travel of the wrist pins between the points *b* to the 75 points *c*. During this time, the bed is held in its proper relative position with respect to the wrist pins by the guard heads, which are at that time in a position to be engaged by the narrow portions 56 of the guard shoes. 80 If it is desired to turn the press in a reverse direction, the bed is carried over the space during which the wrist pins move from the points *c* to the points *b* by the driving action of the curved faces 58 of the guard heads 85 upon the narrow portions 56 of the guard shoes.

Having thus fully described my invention, what I claim as new, and desire to secure by Letters Patent, is:

1. In a mechanical movement, a reciprocable body, a pair of rotary wrist-pins for effecting the reversing of the movement of said body at the ends of the travel of the latter, and reversing shoes carried by said body and cooperating with said wrist-pins, said wrist-pins entering said shoes transversely of the movement of said body and from opposite directions.

2. In a mechanical movement, a reciprocable body, a pair of rotary wrist-pins for effecting the reversing of the movement of said body at the ends of the travel of the latter, and reversing shoes carried by said body and cooperating with said wrist-pins, each of said shoes being disposed mainly on that side of the longitudinal center of said body which is opposite to the end at which the reversal it effects occurs and to extend oppositely to the other in a direction transversely of the movement of said body.

3. In a mechanical movement, a reciprocable body, a pair of rotary wrist-pins for effecting the reversing of the movement of said body at the ends of the travel of the latter, and reversing shoes carried by said body and cooperating with said wrist pins, each of said shoes being placed at an angle of less than 90° to the plane of reciprocation of said body, and being disposed mainly on that side of the longitudinal center of said body which is opposite to the end at which the reversal it effects occurs and to extend oppositely to the other in a direction transversely of the movement of said body.

4. In a mechanical movement, a reciprocable body, a pair of rotary wrist-pins for effecting the reversing of the movements of said body and disposed with their ends extending in opposite directions transversely

of the movement of said body, and reversing shoes carried by said body and cooperating with said wrist-pins.

5. In a mechanical movement, a reciprocable body, a pair of rotary wrist-pins for effecting the reversing of the movements of said body and disposed with their ends extending in opposite directions transversely of the movement of said body, and reversing shoes carried by said body and cooperating with said wrist-pins, each of said shoes being disposed mainly on that side of the longitudinal center of said body which is opposite to the end at which the reversal it effects occurs.

6. In a mechanical movement, a reciprocable body, reversing shoes carried by said body, two racks associated with said body, rotary reversing mechanism having means cooperating with said shoes for reversing the bed, two pinions driven at face speed with said mechanism, and means for shifting first one of said pinions into operative relation with one of said racks and then the other 25 pinion into operative relation with the other rack.

7. In a mechanical movement, a reciprocable body, reversing shoes associated with said body, two racks associated with said body, two reversing wheels having means cooperating with said shoes for reversing the bed, two pinions driven at face speed with said reversing wheels, and means for shifting first one of said pinions into operative 30 relation with one of said racks and then the other pinion into operative relation with the other rack.

8. In a mechanical movement, a reciprocable body, reversing shoes associated with 40 said body, two reversing wheels having means cooperating with said shoes for reversing the bed, two pinions, each meshing with one of said wheels and adapted to mesh with one of said racks, and means for shifting first one of said pinions into operative 45 relation with one of said racks and then the

other pinion into operative relation with the other rack.

9. In a mechanical movement, a reciprocable body, reversing shoes associated with 50 said body, each disposed mainly on that side of the center of said body opposite to that at which the reversal it effects occurs, two racks associated with said body, two reversing wheels having means cooperating with 55 said shoes for reversing the bed, two pinions driven at face speed with said reversing wheels, and means for shifting first one of said pinions into operative relation with one of said racks and then the other pinion into 60 operative relation with the other rack.

10. In a mechanical movement, a reciprocable body, reversing shoes associated with said body, said shoes being placed at an angle of less than 90° to the plane of reciprocation 65 of said body and each being disposed mainly on that side of the center of said body opposite to that at which the reversal it effects occurs, two racks associated with said body, two reversing wheels having means cooperating with said shoes for reversing the bed, two pinions driven at face speed with said reversing wheels, and means for shifting first one of said pinions into operative 70 relation with one of said racks and then the other pinion into operative relation with the other rack.

11. In a mechanical movement, a reciprocable body, reversing shoes associated with said body, two racks associated with said body, two reversing wheels having wrist-pins extending therefrom in opposite directions, each of said wrist-pins cooperating with one of said shoes for reversing the bed, two pinions driven at face speed with said 80 reversing wheels, and means for shifting first one of said pinions into operative relation with one of said racks and then the other pinion into operative relation with the other rack.

BURT F. UPHAM.
